UNITED STATES PATENT OFFICE

2,577,456

COMBINATION HINGE

John P. Doman, Los Angeles, Calif., assignor to
Victor P. Doman, Los Angeles, Calif.

Application November 9, 1945, Serial No. 627,607

6 Claims. (Cl. 16—142)

1

This invention relates to hinges and more especially to a combination hinge having check features for restraining a hinged structure in closed or opened position.

An object of the invention is to provide a simple, practical and inexpensive device of the character described.

Another object of the invention is to provide an improved combination hinge and door check adapted for checking the door in closed or opened position.

A further object is to provide in a hinge check features whereby a hinged structure such as a door may be checked in selected open positions as well as closed position.

An additional object is to provide a combination hinge and door check adapted for use with doors, windows, transoms, cupboard and cabinet doors and other uses of like character.

Other objects and advantages will appear and be brought out more fully in the following specification, reference being had to the accompanying drawing wherein:

Figure 1 is an elevation view of a combination hinge embodying a form of my invention and shown in connection with a door and jamb.

Figure 2 is an elevation view showing the opposite side of the hinge shown in Figure 1.

Figure 3 is an enlarged sectional view taken along the line 3—3 of Figure 1.

Figure 4 is a view similar to Figure 3 showing the relation of the parts with the door closed.

Figure 5 is a view similar to Figure 1 showing a modified form of my invention.

Figure 6 is an elevation view showing the opposite side of hinge shown in Figure 5.

Figure 7 is an enlarged sectional view taken along the line 7—7 of Figure 5.

Figure 8 is a view similar to Figure 7 showing a further modified form of my invention.

Figure 9 is a view similar to Figure 8 showing the parts in the position assumed when the door is closed.

Figure 10 is a fragmentary view showing a modified check element and mode of attaching to a hinge butt.

Referring more particularly to the drawing and especially to Figures 1—4, I show a combination hinge comprising a pair of butts 10 and 11 pivotally secured together by a pin 12 and secured as by screws 13 to a jamb 14 and door 15 respectively. Jamb 14 is formed with a recess 16 and door 15 is formed with a recess 17 to accommodate the check structure about to be described.

Butt 11 is formed with a substantially rec-

2

tangular aperture 18 and butt 10 is formed with a rectangular aperture 19 and a pair of lugs 20. I show a check element 21 which has a somewhat U-shaped formation formed of a strip of resilient material such as spring steel. Element 21 has a somewhat circular center portion 22, and a pair of ends 23 positioned in aperture 19. Ends 23 are formed with apertures 24 for engaging lugs 20 in the opposite sides of aperture 19.

Butt 11 has a substantially rectangular aperture 18 through which the center portion 22 of element 21 extends, as shown in Figure 4, when in the closed position of the door, portion 22 extending into recess 17 of door 14.

The operation of the invention as thus far described should be apparent from the foregoing description. Element 21 is seen to be securely attached to butt 10 by the resiliency of ends 23 and the engagement of apertures 24 and lugs 20.

Ends 23 are sprung inwardly to permit movement of butt 11 and aperture 18 into and out of engagement with spring 21. The curved enlargement 22 thus frictionally engages the opposite sides of aperture 18 and effectively checks the opening movement of the door. Due to the gradual curve of spring 21 the movement of the hinge butt 11 into or out of checking engagement therewith occurs substantially silently and no loud snapping action occurs.

In Figures 5—9, I show a modified form of my invention. In these figures I show butts 30 and 31 secured together by a bearing pin 32 and secured as by screws 33 to a door 34 and jamb 35 respectively, door 34 having a shallow recess 36 and jamb 35 having a deep recess 37.

Butt 31 has a pair of rectangular apertures 38 and 39 forming an abutment bar 40 while butt 30 has a pair of rectangular apertures 41 and 42 forming an abutment bar 43.

The check element of these figures is indicated at 44 and comprises an elongated flat strip of resilient steel or the equivalent having a lip 45 extending through apertures 41 and 42, this lip being formed with a curved end 46 which extends into aperture 42, thus by clamping action securing the element 44 to bar 43 of butt 30. A lug 46a is formed as shown and engages the outer side of bar 43.

Element 44 has an undulating formation providing a plurality of curved cam-like portions 47 adapted to engage edge portions of aperture 38 when the element moves through aperture 38 and into recess 37 of the jamb 35. Element 44 has a bent end portion 48 formed with a flange 55 49 forming a hook-like abutment for engaging

abutment bar 40 for limiting the open movement of butt 30 and door 34.

Figure 7 shows the check element 44 applied to a hinge whereby the door 34 may be opened by a 180 degree movement and will be checked in that position. Figure 8 shows a modified check element applied to a hinge for a door which may be checked at a 90 degree position. Figure 9 shows the door of either Figure 7 or Figure 8 in closed position with the check element 44 extended into recess 37.

Having thus described my invention what I claim and desire to secure by Letters Patent is:

1. A combination hinge as described comprising a pair of pivoted butts, one of said butts having an aperture, and a resiliently deformable check element secured to the other butt adapted to pass into and out of said aperture and frictionally engage opposite edge portions of the aperture of said first butt, said check element having a resilient securing engagement with said second butt.

2. A combination hinge as described comprising a pair of pivoted butts, one of said butts having a substantially square aperture, and a resiliently compressible check element extending through an aperture in and secured to the other butt adapted to pass into said first aperture and frictionally engage opposite side edge portions of the aperture of said first butt.

3. A combination hinge as described comprising a pair of pivoted butts, one of said butts having an aperture and a compressible check element secured to the other butt adapted to pass into said aperture and frictionally engage an edge of said first butt, said element being formed of a U-shaped resilient strip having a normal width in excess of said aperture and adapted to be compressed by movement through said aperture.

4. A combination hinge as described, comprising a pair of pivoted butts, one of said butts having an aperture formed with a lug extending into said aperture, and a resilient check element secured to said butt and formed with an aperture

to engage said lug, said other butt having an aperture and said check element being adapted to pass into and to frictionally engage the aperture of said other butt when one of said butts is rotated toward the other.

5. A combination hinge as described, comprising a pair of pivoted butts, one of said butts having an aperture formed with a lug extending into said aperture and a resilient U-shaped check element secured to said butt and formed with an aperture to engage said lug, said other butt having an aperture and said check element being adapted to pass into and to resiliently engage the aperture of said other butt when one of said butts is rotated toward the other.

6. A combination hinge as described, comprising a pair of pivoted butts, one of said butts having an aperture formed with a pair of lugs extending into said aperture and a resilient U-shaped check element secured to said butt and formed with apertures to engage said lugs, said other butt having an aperture and said check element being adapted to pass into and to resiliently engage the aperture of said other butt when one of said butts is rotated toward the other.

JOHN P. DOMAN.
